LEWIS P. PEASE, OF McCORDSVILLE, INDIANA.

Letters Patent No. 77,087, dated April 21, 1868.

IMPROVEMENT IN PORTABLE FENCE.

The Schedule referred to in these Letters Patent and making part of the same.

TO ALL WHOM IT MAY CONCERN:

Be it known that I, LEWIS P. PEASE, of McCordsville, in the county of Hancock, and State of Indiana, have invented certain new and useful Improvements in Portable Fences; and I do hereby declare that the following is a full, clear, and exact description thereof, reference being had to the accompanying drawings, and to the letters of reference marked thereon, which form a part of this specification, in which—

Figure 1 represents a plan view of my fence.

Figure 2 is a side elevation of the same.

The nature of my invention consists in a worm-fence so constructed that a gate may be made of any of the short panels used in making said fence.

The letter A, fig. 2, represents several panels of my fence in position. B designates the longitudinal and horizontal rails, of which there are two to each panel. The said rails are perforated at suitable distances to receive the upright bar pales d. C represents the long panels, and D the short panels of my fence. The rails of the long panels C are made to extend sufficiently far beyond the pales d to allow the ends of the rails in the short panels C to pass between them, when said short panels are in position. The projecting ends of the rails are perforated to correspond with a similar perforation near the ends of short panel C. Through these perforations the bar e is made to pass, when the long and short panels are placed in position, as seen in fig. 2. By removing the bar e at one end of the short panel, the bar e at the opposite end will answer as a hinge upon which said panel can be swung around, so as to answer the purpose of a gate.

In order to give the required stability to the fence, the bars e will be sharpened at their lower end, and made sufficiently long to admit of their being driven some distance in the earth. The fence will also be strengthened by the braces g, which bind the top rails of the long and short panels together.

The advantage of this fence in affording an egress from a field at any desired point is obvious, and the facility with which this desired end is accomplished, is both simple and effectual.

Having thus fully described my invention, what I claim, and desire to secure by Letters Patent, is—

The alternate long and short panels, so arranged that the adjustable brace g will bind two long and one short panel together, in combination with the long bars e e, as and for the purpose set forth and described.

In testimony that I claim the foregoing as my own, I affix my signature in presence of two witnesses.

LEWIS P. PEASE.
